DESIGN FOR CARPET.

SPECIFICATION forming part of Design No. 27,051, dated May 11, 1897.

Application filed April 2, 1897. Serial No. 630,479. Term of patent 31 years.

To all whom it may concern:

Be it known that I, ANNA K. MAY, a citizen of the United States, residing at the city of Philadelphia, in the county of Philadelphia and State of Pennsylvania, have invented and produced a new and original Design for a Carpet or other Fabric, of which the following is a specification, reference being had more particularly to the accompanying drawing, illustrating the same and forming part hereof.

The leading feature of my design comprises an oriental pattern made up of comparatively large separated figures with smaller ones dropped on the ground.

15 In the drawing, *a* is the body, *b* the border, and *a b* the complete carpet.

c are comparatively large figures made up of smaller ornaments and generally rectilinear in their appearance.

20 *e* are comparatively small figures, which are generally rectangular in their make up and which are dropped on the ground *f* between the figures *c*.

The design of my invention will be best understood by reference to the accompanying 25 drawing, and it may be expressed in different colors or combinations of colors and applied to velvet, Wilton, Brussels, ingrain, and other carpets.

What I claim as my invention, and desire 30 to secure by Letters Patent, is—

1. In a design for a carpet, the body *a*, substantially as shown.

2. In a design for a carpet, the border *b*, substantially as shown.

3. The design for a carpet consisting of the body *a*, and border *b*, substantially as shown. 35

In testimony whereof I have hereunto signed my name.

ANNA K. MAY.
